(57) **CLAIM**

The ornamental design for a ring, as shown and described.

DESCRIPTION

FIG. 1 is a top and left side perspective view of the ring;

FIG. 2 is a top view thereof;

FIG. 3 is a front view thereof;

FIG. 4 is a rear view thereof;

FIG. 5 is a left side view thereof; the right side view is a mirror image; and,

FIG. 6 is a bottom view thereof.

The broken lines appearing in FIGS. 1, 2, and 5 of the drawings are for illustrative purposes only and do not form part of the design claim.
